AWNING

Mynard R. Lorenz and Clarence A. Brahm,
Pittsburgh, Pa.

Application January 15, 1946, Serial No. 641,191

1 Claim. (Cl. 20—57.5)

1

This invention relates to awnings in the conventional form of rooflike covers extending over or before porches, windows, or other places, as shelters from the sun, rain, or wind.

Important objects and advantages of the invention are to provide an awning of the character described, which is entirely constructed of light weight metallic material preferably aluminum, which is primarily designed and intended to be installed as a permanent structure, which is conveniently operable and adjustable to the open position to admit the maximum of light and ventilation therethrough, which is tensionally held in the closed position, which is simple in its construction and arrangement, durable and efficient in its use, compact, noiseless, attractive in appearance, and comparatively economical in its manufacture, installation, and maintenance.

With the foregoing and other objects in view which will appear as the description proceeds, the invention resides in the novel construction, combination, and arrangement of parts herein specifically described and illustrated in the accompanying drawings, but it is to be understood that the latter are merely illustrative of an embodiment of the invention, and that the actual needs of practice and manufacture may require certain mechanical variations from the embodiment shown. It is, therefore, not intended to limit the invention to the disclosure thereof herein illustrated, but rather to define such limitations to the scope of the claim hereunto appended.

In the drawings wherein like numerals of reference designate corresponding parts throughout the several views:

Figure 1 is a perspective view of a metallic, adjustable awning constructed in accordance with the invention.

Figure 2 is a transverse cross sectional view of the awning, taken on line 2—2, Figure 1.

Figure 3 is a transverse, cross sectional view of the awning with the embodied louver panels being disposed in the open positions.

Figure 4 is an enlarged, transverse cross sectional view of a louver panel, and illustrating the connection of the latter with its supporting and operating elements.

Referring in detail to the drawing 1 represents the entire supporting frame of the awning. The frame is rigid and is preferably constructed of fabricated structural metal. The frame is fixedly secured against the building structure 2, against which the awning is to be attached. The frame includes a plurality of parallel and angularly disposed frame members 3, which are posi-

tioned at an angle from the horizontal to provide the required pitch or degree of roof slope for the awning to drain rain from the latter.

An angularly disposed frame member 3 is positioned at each end of the frame 1, and as many others are provided therebetween, in regularly spaced relation to each other, as are required to properly support and to prevent sagging of the louver panels 4. The louver panels are mounted 10 on the frame members 3, and the number of the latter required is determined by the length of the span of the awning.

An end wall 5 is permanently secured against each end of the frame 1 to close the respective 15 ends of the latter, and a front wall 6 is secured against the front of the frame. The end and front walls 5 and 6 may each be in the form of an integral structure, or each may be constructed of a plurality of separate sections. The end and front walls 5 and 6 are preferably shaped in an 20 appropriate ornamental design to enhance the appearance and attractiveness of the awning, and the lower ends thereof depend below the frame 1, thereby giving the improved metal awning the 25 general appearance of the conventional type of awnings, particularly of awnings for homes.

The roof of the awning comprises the plurality of louver panels 4, and the upper and lower roof panels 7 and 8. All of the panels are disposed 30 horizontally lengthwise in parallel relation to each other. The roof panel 7 is secured to the upper end of the frame members 3 against the building structure 2, and the lower roof panel 8 is secured in position at the lower ends of the 35 frame members 3.

An important feature of the invention is the construction and assembly of the louver panels 4. Each of the louver panels is formed with a rear reenforcing flange 9 and with a front reenforcing flange 10, which flanges 9 and 10 extend 40 throughout the length of the louver panel, and serve to adequately stiffen the latter.

The rear flange 9 depends at right angles from the rear edge of the louver panel 4. The front 45 flange 10 likewise depends at right angles from the louver panel, but is spaced from the front edge of the latter to provide the overlapping front portion 11 forwardly thereof.

When the louver panels 4 are assembled on 50 the frame 1 and are in the closed position, the rear flanges 9 thereof will seat on the top of the angularly disposed frame members 3. The front portion 11 of each louver panel will overlap the top of the rear edge margin portion of the louver panel that is disposed adjacent to and directly

3

forward thereof, and the front flange 10 will be thereby held in slightly spaced relation to the frame members 3, as clearly illustrated in Figure 2.

Each of the louver panels 4 carries a plurality of pivoting brackets 12 which are secured in fixed position against the underside of the louver panel. In each of the louver panels one such pivoting bracket 12 is disposed laterally of and against each frame member 3 embodied in the frame 1.

Each of the brackets 12 is pivotally joined to the respective frame members 3, at a point adjacent to and below the rear flange 9 of the associated louver panel 4, by means of a pivoting pin 13, whereby the rear of each of the louver panels is shiftably attached to the frame members 3.

Each of the brackets 12 includes a depending arm 14, which has its lower end pivotally connected to an operating bar 15, by means of a pivoting pin 16. All of the arms 14 of the brackets 12 that are pivotally joined to a common frame member 3, are likewise pivotally connected to a common operating bar 15.

The forward end of each of the operating bars 15 is connected to a pull rope 17, which latter first extends forwardly and through a pulley 18 at the front of the frame 1, and then rearwardly from said pulley 18 through another pulley 19 at the rear and near the top of the frame 1.

It will be obvious that a pull on the ropes 17 will draw the operating bars 15 in the forward direction, whereby all of the louver panels 4 will be simultaneously shifted to the open positions on their pivotal connections with the frame members 3, as clearly illustrated in Figure 3. The louver panels 4 are maintained in the open positions by securing the free ends of the pull ropes 17 to a suitable fastener 20 that is fixed to the building structure 2. When the pull ropes 17 are released from the fastener 20, the louver panels will simultaneously shift to their closed positions by gravity action.

A spiral spring 21 connects with the rearward end of each of the operating bars 15 and with the frame 1. The normal action of the springs 21 tends to shift the louver panels 4 from the open to the closed positions, and to tensionally hold the latter in the closed positions. Such tensional action of the springs 21 will assure a leakproof engagement at the overlapping portions of the louver panels, and prevent the shifting and rattling of the latter from untoward weather conditions.

When in the open positions, the louver panels 4 are preferably disposed on a level horizontal plane, as shown in Figure 3, as such positions of

the louver panels provide the maximum openings and capacity for the admittance of light and ventilation through the open louver panels. The opening movements of the louver panels are limited by the engagement of the free lower edges of the rear flanges 9, of the louver panels, against the top of the frame members 3 when the louver panels are in the proper open positions.

It will here be noted that the improved metal awning, being adjustable and designed for permanent installation, is particularly adaptable for use on homes to replace the conventional type of canvas awnings, as its use eliminates the need for seasonal installation and removal. Further, the metal awning may be readily painted in single or variegated colors to provide any desired ornamental or decorative appearance.

The present invention provides a most substantial and efficient structure of its kind, which may be economically manufactured and installed, and which may be successfully and conveniently employed for the purposes and in the manner herein set forth.

What we claim is:

26 In a metal awning construction of the class described, an elongated sheet metal louver panel, a reenforcing flange formed integral with the rear edge of said panel and depending at right angles from the latter, a reenforcing front portion formed integral with the front edge of said panel and being inturned flatly against the under face of the front portion of said panel, and a reenforcing flange formed integral with the rear edge of said inturned front portion and being disposed adjacent to but spaced from the front edge of said panel, said last-mentioned flange depending at right angles to said panel and being formed by folding flatly together the rear portion of said inturned front portion to provide a flange structure of double material thickness.
